(57) **CLAIM**

We claim the ornamental design for a water pail for drying machine, as shown and described.

DESCRIPTION

FIG. 1 is a front perspective view of a water pail for drying machine showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view thereof;

FIG. 9 is a cross-sectional view taken through line 9-9 of FIG. 2;

FIG. 10 is a cross-sectional view taken through line 10-10 of FIG. 3; and,

FIG. 11 is a front perspective view thereof, in an environment of use.

The broken lines in the figures depicting portions of the water pail for drying machine form no part of the claimed design. The broken lines in FIG. 11 illustrating a drying machine are environment that form no part of the claimed design.

1 Claim, 11 Drawing Sheets
